UNITED STATES PATENT OFFICE.

WILLIAM BENTLEY AND WILLIAM J. D. THOMPSON, OF TORONTO,
ONTARIO, CANADA.

SLIDING WINDOW AND WINDOW-FRAME.

No. 834,453.

Specification of Letters Patent.

Patented Oct. 30, 1906.

Application filed February 25, 1904. Renewed April 16, 1906. Serial No. 311,852.

To all whom it may concern:

Be it known that we, WILLIAM BENTLEY and WILLIAM J. D. THOMPSON, of the city of Toronto, in the county of York and Province 5 of Ontario, Canada, have invented certain new and useful Improvements in Sliding Windows and Window-Frames; and we hereby declare that the following is a full, clear, and exact description of the same.

10 We have found that in the construction of the window and window-frame the necessity of allowing for the swelling and shrinking of the window-sash and its guideways may be dispensed with by fitting each side of the 15 window-frame with a single window-guide and providing the window-sash with guiding members, each having two contact-points to engage the opposite sides of the window-guide and hold the window-sash relatively 20 thereto when stationary and during its sliding movements.

To effect a substantially tight contact of the window-sash when closed with the window-guides, the latter have on their outer 25 surfaces raised offsets onto which ride the outer contact-points of the guiding members as the window-sash slides into its closed position to draw it tightly against the inner or adjacent faces of the window-guides and not 30 only prevent the inlet of air-currents between the window-sash and guideways, but also render it impossible for the window-sash to vibrate under ordinary conditions. When 35 opening the window, the outer contact-points move from the raised offsets as the window-sash begins to slide into its open position, and the inner contact-points then exert themselves upon the inner surfaces of the window-guides to press the window-sash away from 40 them, so that by being clear of contact with the window-guides it may slide freely in its fixed pathway.

In the drawings, Figure 1 is a front elevation of a window-frame and sliding window-sash adapted for building purposes. Fig. 2 is a transverse section on the lines *b b*, Fig. 1. Fig. 3 is a perspective view of one of the guiding members for the window-sash. Fig. 3^a is a vertical section on the line *a a*, Fig. 5. 45 Fig. 3^b is a transverse section on the line *b b*, Fig. 5. Fig. 4 is a perspective view of a part of one of the window-guides. Figs. 4^a and 4^b are vertical and transverse sections, respec-

tively, of a portion of one of the window-guides.

55

Like letters of reference refer to like parts throughout the specification and drawings.

The window-sash *a*, which is made to fit loosely between the sides of the window-frame *b*, has guiding members *c*, the contact-points of which ride on the opposite sides of the window-guides *d*, fastened to or forming part of the sides *b'* of the window-frame and extending from the top to the bottom of the slideway for the window-sash.

65

To prevent any material variation in the slideway, the window-guides *d* are preferably made of metal of a uniform gage throughout their entire length, and riding on the opposite sides of the window-guides *d* are the inner and outer contact-points *f* and *g*, respectively, of the guiding members *c*, located at or near the corners of the window-sash to maintain it throughout its entire length properly positioned relatively to the window-guides.

75

By reference to Figs. 3, 3^a, and 3^b of the drawings it will be noticed that each guiding member *c* consists of a bifurcated plate, the one arm *h* of which is adapted to lie against the adjacent surface of the window-sash and be fastened thereto and the other arm *i* of which projects outwardly from the arm *h* and preferably parallel with the window-sash to form the pathway for the window-guide *d*. In the arm *i* is an elongated slot *j*, 80 and connected to the opposite ends of the arm *i* and on its outer side is a spring *k*, having an elongated slot *l* registering with the slot *j*, and movable in the slots *j* and *l* is an antifriction-roller *m*, having its spindles *o* 85 contained between the adjacent faces of the arm *i* and spring *k*. Extending from the arm *h*, at an opposite angle to the arm *i*, is a stud *p*, upon which is mounted an antifriction-roller *q*, opposed to the antifriction-roller *m*, 90 the stud *p* and antifriction-roller *q* for the purpose of economy of space being contained in a recess *r*, formed in the window-sash.

95

By reference to the drawings it will be noticed that the slotted arms *i* of the guiding members at each side of the window-sash align and overlap the window-guides to provide a sufficient surface for the outer and inner contact-points of the guiding members to ride upon, and by using antifrictional rollers 100 for these contact-points the wear upon the

105

guiding members and window-guides is minimized and the window-sash can freely move in its slideways.

During the sliding movement of the window-sash the inner and outer contact-points engage the window-guide and hold the window-sash relatively thereto, the inner contact-points or antifrictional rollers *q* being so arranged as to exert themselves against the inner surfaces of and press the window-sash away from the window-guides to avoid any frictional contact therewith during its sliding movement, the spring *k* yielding sufficiently to allow of the displacement of the outer contact-points and compensate for any variation in the gage of the window-guide.

The window-sash owing to its loose fit between the sides of the window-frame when pressed away from the window-guides provides crevices or inlets for the air-currents between its side edges and the adjacent surfaces of the sides of the window-frame, and to entirely close these inlets when the window is shut the outer surfaces of the window-guides are provided with raised offsets *s*, onto which ride the outer contact-points of the guiding members as the window-sash moves into its closed position. These outer contact-points when they have engaged the raised offsets draw the window-sash tightly against the adjacent faces of the window-guides with sufficient pressure to completely close any crevices or inlets which may have previously existed between the edges of the window-sash and sides of the window-frame. The raised offsets *s* are preferably formed by indenting the inner faces of the window-guides, so that indented seats may be provided for the inner contact-points when the outer contact-points are seated upon the raised offsets to relieve the guiding members of the contending strains to which they would have been subjected by the contact-points if the indented seats had not been provided for the inner contact-points, as in this way the relative distance of the inner and outer contact-points from each other will be maintained during the entire movement of the window-sash and when it is at rest.

By reference to Fig. 1 of the drawings, it will be noticed that the top of the window-frame is fitted with a window-stop *t* corresponding to the window-guides *d*, so that when the window-sash is drawn tightly against the window-guides its top edge will engage the adjacent face of the window-stop *t* and prevent the ingress of the air-currents between its top edge and top of the window-frame. By this means we are able to loosely fit the window-sash between the opposite sides of the window-frame and at the same time establish a perfect contact between the window-sash and the window-guides and stops to close all crevices between the window-sash and window-frame when the window-sash is in its closed position.

fit the window-sash between the opposite sides of the window-frame and at the same time establish a perfect contact between the window-sash and the window-guides and stops to close all crevices between the window-sash and window-frame when the window-sash is in its closed position.

dow-sash is in its closed position. We are also able by this construction to compensate for the necessity of allowing for the shrinkage and swelling of the parts of the window, and we are further able to prevent any vibration of the window-sash either while it is in motion or at rest. To fasten the window-guides to the window-frame, we prefer to longitudinally groove the window-frame sides and place the window-guides in these longitudinal grooves 3, holding them therein by washers 4, countersunk in the window-frame sides and partly contained in longitudinal slots 5 in the window-guides, the length of the slots being less than the diameter of the washers, to enable the washers to contact the ends of the slots and prevent the longitudinal displacement of the window-guides in the window-frame grooves and their lateral displacement therefrom, which is effected by their contact with the side edges of the slots.

To hold the window-sash in a closed or open position, a suitable locking device, such as that shown at *o'* and *p'*, may be used.

Having thus fully described my invention, what I claim as new, and desire to secure by Letters Patent, is—

1. In a sliding window, the combination of the window-frame, a window-sash contained therein, a single window-guide at each side of the window-frame overlapping the inner faces of the sides of the window-sash, and guiding members on the window-sash to constantly engage the window-guides and position the window-sash relatively thereto.

2. In a sliding window, the combination of a window-frame, a window-sash contained therein, a single window-guide at each side of the window-frame overlapping the inner faces of the sides of the window-sash, and guiding members on the window-sash each having two contact-points for constantly engaging opposite sides of the window-guides, to position the sash relatively thereto.

3. In a sliding window the combination of the window-sash, window-guides therefor, guiding members on the window-sash to engage the window-guides, and means for drawing the window-sash to the window-guides as it moves into its closed position.

4. In a sliding window the combination of the window-sash, window-guides therefor, guiding members on the window-sash to engage the window-guides, means for drawing the window-sash to the window-guides as it moves into its closed position and means for moving the window-sash away from the window-guides as it begins to move into its open position.

5. In a sliding window the combination of the window-sash, window-guides therefor, guiding members for the window-sash each having two contact-points to engage the opposite sides of the window-guides, raised offsets for the window-guides positioned to be

engaged by the contact-points as the window-sash moves into its closed position.

6. In a sliding window the combination of the window-sash, window-guides therefor, 5 guiding members for the window-sash, each having two contact-points to engage the opposite sides of the window-guides, indented offsets for the window-guides positioned to be engaged by the contact-points as the window-sash slides into its closed position, the outer contact-points of the guiding members engaging the raised surfaces of the offsets to draw the window-sash against the window-guides and the inner contact-points being 10 then adapted to enter the indented recesses.

7. In a sliding window the combination of the window-sash window-guides therefor, guiding members for the window-sash, each having two contact-points to engage the opposite sides of the window-guides, indented offsets for the window-guides positioned to be engaged by the contact-points as the window-sash slides into its closed position, the outer contact-points of the guiding members engaging the raised surfaces of the offsets to draw the window-sash against the window-guides, the inner contact-points being then 15 adapted to enter the indented recesses, and

to exert themselves upon the inner surfaces of the window-guides as the window-sash begins to slide into its open position to move it away from the same. 30

8. In a sliding window the combination of the window-sash, a single window-guide at each side thereof, guiding members for the window-sash, each consisting of two opposite sitely-disposed antifriction-rollers to engage the opposite sides of the window-guides and supporting means therefor to hold them relatively positioned to each other and to the window-guide. 35

9. In a sliding window the combination of the window-sash, window-guides therefor, guiding members for the window-sash, each consisting of two oppositely-disposed anti-friction-rollers to engage the opposite sides of the window-guides and supporting means therefor to rigidly hold one of the antifriction-rollers and to yieldingly hold the other to engage the opposite sides of the window-guides. 40
